(57) CLAIM

The ornamental design for a cosmetic applicator with cap, as shown and described.

DESCRIPTION

FIG. 1 is an exploded perspective view of a cosmetic applicator with cap showing my new design;

FIG. 2 is a side view thereof;

FIG. 3 is a side view of the cosmetic applicator;

FIG. 4 is a top view of the cosmetic applicator; and,

FIG. 5 is a bottom view of the cosmetic applicator.

The cap is omitted in FIGS. 3 and 4 for ease of illustration only.
